[57] CLAIM

The ornamental design for a sliding clamp for easels, as shown.

DESCRIPTION

FIG. 1 is an isometric view of the clamp embodying my ornamental design;

FIG. 2 is an elevation view of the left side of the clamp of FIG. 1;

FIG. 3 is a front elevation view of the clamp of FIG. 1;

FIG. 4 is an elevation view of the right side of the clamp of FIG. 1;

FIG. 5 is a rear elevation view of the clamp of FIG. 1;

FIG. 6 is a top view of the clamp of FIG. 1, and

FIG. 7 is a bottom view of the clamp of FIG. 1.
